RAIL JOINT

Louis Gagnon, Sault Ste. Marie, Ontario, Canada

Application June 23, 1947, Serial No. 756,434
In Canada May 29, 1947

3 Claims. (Cl. 238—212)

1

This invention relates to railroad rail joints.

An object of the invention is to provide an improved joint for rails, which is of simple and inexpensive manufacture, and by means of which a pair of rails may be readily and firmly joined. Another object is to provide a fish plate joint for rails wherein the fish plates constitute supporting members and form a part of the vertical column of the rail to give substantially complete rigidity to the joint whereby relative movement of the rail ends is eliminated and unevenness in the rail surface avoided. Another object is to provide a fish plate joint wherein the fish plates, in the assembled joint, are placed under compression with the web of the rails under tension to provide a joint which will maintain its effective rigidity under prolonged operating conditions.

Other objects, details and advantages of the invention will appear from the ensuing description with particular reference to the accompanying drawing, in which:

Figure 1 is a transverse section through a rail showing a joint structure in tightened relation,

Figure 2 is a transverse section showing the joint structure in loosened relation,

Figures 3 and 4 are transverse sections showing two modified forms of the invention, and

Figure 5 is a side elevation of the joint structure shown in Figure 3.

In accordance with the invention, there is provided a base plate 5 which is adapted to provide a supporting surface for the adjoining end portions of a pair of rails. The width of the upper rail base engaging surface of the plate 5 is substantially coextensive with that of the rail base. The base plate 5 is in slight degree transversely bowed or curved to present a convex rail engaging surface whereby the edge portions thereof must be sprung upwardly a short distance before engagement of such edge portions with the plane under surface of the rail occurs. The base plate 5 is provided with marginal upwardly extending vertically directed flanges 6, the inner surfaces of which are in substantial abutment with the edges of the rail base 3. The under surface of the base plate may be provided with longitudinal ribs 7 to prevent side slipping of the structure with respect to the supporting surface on which the device is mounted. Laterally extending flanges 8 may be provided to facilitate attach-

2

ment to the supporting surface by spikes or the like.

Referring particularly to Figures 1 and 2, the upper edge portion of each flange 6 is bent inwardly to provide a shoulder 9 having an arcuate under surface 10. A pair of fish plates 12, of substantially the same length as base plate 5, are adapted to be placed one on each side of the rails. Each fish plate has a curved inner surface 13 adjacent its upper edge of complementary contour to that of the curved juncture surface between the web and head of the rail. Each fish plate also has a curved inner surface 14 on its lower portion of complementary contour to that of the juncture surface between the web and base of the rail. The fish plate also has a lower portion 15 having a generally curved lower surface constituting a cam or rocker surface 15a for engagement with the upper surface of the base of the rail, and an outwardly extending tail portion 15b which extends slightly upwardly and has a convexly curved contour for engagement with the concave under surface 10 of flange 6. The fish plates are connected together by a plurality of bolts 16 extending through the rail, and nuts 17.

The parts are assembled in position as shown in Figure 2, and the bolts applied and tightened. It will be observed that the lower portions 15 of the plates rock on the base 3 of the rail and, in the initial position of the plates, they are tilted outwardly away from engagement with the web of the rail. On application of the bolts and tightening of the nuts thereon, the plates will be drawn together, which action swings the tail portions 15b upwardly. As such portions move upwardly, they apply a lifting force on the vertical flanges 6 and thus raise the marginal portions of base plate 5, which are adapted to substantially engage the base 3 of the rail in the fully tightened position of the fish plates. This bending movement of the base plate 5 creates a spring tension therein which acts to maintain the assembled joint structure under great tension whereby rigidity of the structure under operating conditions is assured. Moreover, the fish plates are of such dimensions that, as their surfaces 13 and 14 engage the complementary surfaces on the rails, they become jammed between the head and base of the rails, thereby placing the rail web in tension with the

fish plates in compression. Thus, the fish plates become, in effect, a portion of the rail web, which bridges the rail joint and tend to form a continuous web portion. This action not only holds the two adjoining rails in continuous alignment but also increases the strength of the web. Furthermore, when the rails are loaded at the joint, sagging of one rail relative to the other is prevented because the fish plates are jammed against the web and between the head and base of the rails and hence are capable of withstanding the load without sag.

Preferably the fish plates are of maximum possible thickness to provide greatest support without interference by the wheels of a railway car. Thus, it is proposed that the upper outer edge portion of the fish plate should lie, when in fully assembled relation, within one-eighth inch of the lateral surface of rail head, and that the outer face of the fish plate should lie in substantially the same vertical plane as that of the lateral face of the rail head or in slightly outwardly spaced relation with respect thereto.

Referring to Figures 3 and 5, the base plate 18 is similar in structure to base plate 5 and is normally transversely curved or arched. It is provided with longitudinal vertical marginal flanges 19 having a plurality of apertures 20 therein, the upper surface of each of which is preferably curved as indicated at 21. Fish plates 22 are similar in structure to plates 12, but the lower laterally extending tail portion 23 of each plate is provided with a plurality of fingers 24 extending outwardly from the edge thereof and complementary to the apertures 20 in the base plate. The upper surfaces of the fingers are also complementarily curved to engage the surfaces 21 of the apertures. It will be observed that, on assembly of the joint structure, the fingers will exert an upward lifting action on the flanges 19 to place the base plate under tension and in substantially complete engagement with the lower surface of the rail base.

Referring to Figure 4, the base plate 25 is similar in structure to base plate 6 and, in normal condition, is similarly transversely curved. It is provided with vertically extending marginal flanges 26, which have outwardly directed shoulders 27 along the upper edges thereof. Fish plates 28 are also similar in structure to plates 12, but their lower lateral extensions 29 have downwardly projecting portions 30 provided with inwardly extending shoulders 31 adapted to engage the lower surfaces of shoulders 27 on the base plate flanges and thus apply a lifting action thereto.

A shim may be interposed between the base plate 6 and base 3 of the rail to create more tension and compression in the assembly if such increased pressure is required. Such a shim is shown at 32 in Figure 4.

It will be apparent that the same effective results, as described with respect to the modification shown in Figures 1 and 2, are accomplished by use of the modified forms shown in Figures 3 and 4.

I claim:

1. In a joint for adjoining rail ends of the type including head, base and connecting web portions, a base plate transversely curved throughout its length to initially present an upper convex surface to receive and support the base portions of the rail ends upon one or more ties, said plate including upstanding side flanges, a pair of fish plates, each of said fish plates including

a lower portion having a convex under surface adapted to be rockingly and slidably engaged with the upper surface of the rail base flange and a laterally extending tail piece interlocked with a side flange on said base plate and an upper portion which upon rocking of said fish plate inwardly toward the rail web portion wedges against and imparts an upward thrust to the under face of the rail head portion thereby causing a sliding motion of the convex under surface of said fish plates on the upper surface of said rail base flange, and tightening bolts extending through said fish plates and the web portions of the adjoining rail ends for rockingly drawing said fish plates inwardly thus affecting said upward thrust of the fish plates against the head portions of the rail ends and simultaneously exerting a lifting force upon said side flanges to thereby strain the initially convex base plate into contact with the base portions of the rail ends throughout substantially the entire width of the latter.

2. In a joint for adjoining rail ends of the type including head, base and connecting web portions, a base plate transversely curved throughout its length to initially present an upper convex surface to receive and support the base portions of the rail ends upon one or more ties, said plate including upstanding side flanges and each of which flanges includes an inturned portion having a concave under surface, a pair of fish plates, each of said fish plates including a lower portion having a convex under surface adapted to be rockingly and slidably engaged with the upper surface of the rail base flange and a laterally extending tail piece having convex upper surface interlocking with the concave under surface of one of said side flanges and an upper portion which upon rocking of said fish plate inwardly toward the rail web portion wedges against and imparts an upward thrust to the under face of the rail head portion thereby causing a sliding motion of the convex under surface of said fish plates on the upper surface of said rail base flange, and tightening bolts extending through said fish plates and the web portions of the adjoining rail ends for rockingly drawing said fish plates inwardly thus effecting said upward thrust of the fish plates against the head portions of the rail ends and simultaneously exerting a lifting force upon said side flanges to thereby strain the initially convex base plate into contact with the base portions of the rail ends throughout substantially the entire width of the latter.

3. In a joint for adjoining rail ends of the type including head, base and connecting web portions, a base plate transversely curved throughout its length to initially present an upper convex surface to receive and support the base portions of the rail ends upon one or more ties, said plate including upstanding side flanges each provided with a horizontal row of spaced apertures, a pair of fish plates, each of said fish plates including a lower portion having a convex under surface adapted to be rockingly and slidably engaged with the upper surface of the rail base flange and a laterally extending tail piece provided with a plurality of spaced fingers extending into the apertures in the correspondingly positioned side flange on said plate and an upper portion which upon rocking of said fish plate inwardly toward the rail web portion wedges against and imparts an upward thrust to the under face of the rail head portion thereby causing a sliding motion of the convex under surface of said fish plates

on the upper surface of said rail base flange, and tightening bolts extending through said fish plates and the web portions of the adjoining rail ends for rockingly drawing said fish plates inwardly thus effecting said upward thrust of the fish plates against the head portions of the rail ends and simultaneously exerting a lifting force upon said side flanges to thereby strain the initially convex base plate into contact with the base portions of the rail ends throughout substantially the entire width of the latter.
